AUTOMATIC OFF-BEARING ASSEMBLY FOR DRYERS

Arthur H. Beckley, Portland, Oreg., assignor to Moore Dry Kiln Company, North Portland, Oreg., a corporation of Oregon

Filed Nov. 16, 1959, Ser. No. 853,285

2 Claims. (Cl. 214—16.4)

This invention relates to the handling of such materials as sheets of veneer as they are received from a dryer and are required to be placed consecutively on a conveyor for delivery for further processing or handling.

More specifically, the invention relates to the depositing of sheets of veneer individually and consecutively onto a continuous conveyor as such sheets are delivered from a multiple deck dryer and cooler.

Heretofore it has been customary to have such sheets of veneer, when discharged from the dryer and cooler, placed manually on a continuous conveyor, one after the other, so that the sheets can be delivered to stations where the sheets are sorted and graded before being delivered to storage.

The object of the present invention is to provide continuously operating means by which the placing of the individual sheets from the dryer and cooler onto a continuous conveyor will be done mechanically instead of manually.

A related object of the invention is to provide suitable means by which the sheets will be deposited directly onto the continuous conveyor as delivered, instead of being deposited first onto a receiving platform and pile and then placed on the continuous conveyor.

Another object of the invention is to provide an off-bearing assembly which will operate in conjunction with a multiple deck dryer and cooler so as to cause the sheets from the various decks to be delivered onto the same conveyor.

A further object is to provide an automatic delivery control for the decks of the multiple deck dryer and cooler whereby the sheets from consecutive decks will be discharged consecutively, and further to cause only one sheet or sets of sheets at a time to be discharged from the dryer and cooler.

An additional object of the invention is to provide adjustable speed control means for such automatic off-bearing assembly, operating in combination with a multiple deck dryer and cooler, whereby the speed at which the sheets are removed from the decks of the dryer and cooler can be regulated by and coordinated with the speed at which the sheets are being delivered by the dryer and cooler, which in turn can be regulated by the speed for which the dryer is set.

A still further specific object of the invention is to provide a practical "tipple" assembly through the medium of which veneer sheets from a multiple deck dryer and cooler can be quickly and automatically transferred individually to a continuous conveyor.

The manner in which these objects and other advantages are attained with the present invention, and the manner in which the various parts of the off-bearing assembly are caused to function, will be apparent from the following description and explanation with reference to the accompanying drawings.

In the drawings:

FIG. 1A is a diagrammatic side elevation of a multiple deck off-bearing section together with a connected end of the multiple deck dryer and cooler, showing also a portion of the adjacent or receiving end of the moving off-bearing tipple, the driving means for the feeder rolls for the off-bearing section being indicated diagrammatically but the means for controlling the discharge of the

2

veneer sheets from the decks of the off-bearing section onto the tipple being omitted for the sake of clarity;

FIG. 1B is a continuation of FIG. 1A and is an elevation, partly diagrammatic, of the off-bearing tipple leading from the off-bearing section to the endless conveyor;

FIG. 2 is a fragmentary side elevation, partly diagrammatic, of the lower portion of the discharging end of the multiple deck off-bearing section together with a portion of the adjacent receiving end of the tipple, this view being taken from the side opposite that shown in FIG. 1A and illustrating the means for controlling the discharging of the veneer sheets from the decks of the off-bearing section, but omitting the driving means for the feeding rolls in the off-bearing section;

FIG. 3 is a fragmentary plan view taken on line 3—3 of FIG. 2, showing a portion of the discharge control assembly, including pinch wheels and a stop gate;

FIG. 4 is a corresponding perspective view of the same portion of the discharge control assembly;

FIG. 5 is a fragmentary and foreshortened front elevation of the same lower portion of the discharging end of the multiple deck off-bearing section taken on line 5—5 of FIG. 2;

FIG. 6 is a fragmentary section, taken on line 6—6 of FIG. 2, of one of the spring-mounted carriers for one of the pinch wheels, drawn to a larger scale;

FIG. 7 is a fragmentary plan view, taken on line 7—7 of FIG. 1A, of the mechanically-operated switch means which is adjustably driven by connection with the feed rolls of the dryer and cooler and which, in conjunction with time delay relay switches, produces the activation of the circuits to solenoid-operated valves, which control actuation of the air cylinders operating pinch wheels and stop gates for regulating the discharge of the veneer sheets from the various decks of the off-bearing section, and the solenoid-operated valves for hydraulic operating means for the off-bearing tipple;

FIG. 8 is a fragmentary sectional elevation taken on line 8—8 of FIG. 1B, but drawn to a larger scale; and

40 showing part of the means controlling up and down movement of the tipple;

FIG. 9 is an enlarged fragmentary sectional elevation taken on line 9—9 of FIG. 7; and

FIG. 10 is a simplified schematic wiring diagram to

45 illustrate the manner in which the operation of the device is controlled and synchronized.

Referring first to FIG. 1A, the reference 10 indicates the discharging end of a six deck dryer and cooler, the decks of which discharge respectively onto the corresponding decks 12, 13, 14, 15, 16 and 17, of the six deck off-bearing section 11. Each deck of the dryer and cooler 10 is provided with driven feed rolls indicated by the broken lines 68 in FIG. 1A. Each deck of the off-bearing section 11 similarly is provided with driven feed rolls

55 which are connected by endless drive chains 18, 19, 20, 21, 22 and 23 respectively to the forward end rolls 24, 25, 26, 27, 28 and 29 respectively, these end rolls in turn being connected together by a series of endless chains 30. A drive sprocket 31 for the end roll 24 is driven

60 by an endless chain connection 32 with a sprocket mounted on a bottom delivery roll 33, and the delivery roll 33 is driven by an endless chain connection 39 with a motor M. Pairs of delivery rolls 33 and 33', 34 and 34', 35 and 35', 36 and 36', 37 and 37', and 38 and 38',

65 are mounted at the discharge ends of the six decks of the off-bearing section respectively. The pair of delivery rolls 33 and 33' on the lowest deck of the off-bearing section are connected by an endless chain 40, and the delivery rolls in each of the other pairs are similarly connected together. The rolls 33, 34, 35, 36, 37 and 38 are connected together by a series of endless chains, as indicated. Thus all the delivery rolls are driven in

unison by the motor M, and all the series of feed rolls likewise are driven in unison by the same motor, but the delivery rolls are driven at greater speed than the feed rolls, as apparent from FIG. 1A. The sheets of veneer are moved along by the feed rolls on the various decks of the off-bearing section 11 (from left to right as viewed in FIG. 1A) until they reach the more rapidly rotating set of delivery rolls. As each sheet reaches the delivery rolls on its deck it is temporarily restrained, by a stop fence hereinafter described, until the adjacent end of the moving transfer assembly 41, commonly known as a "tipple," comes into registration with that deck, whereupon the stop fence is raised and the delivery rolls, with the assistance of cooperating pinch wheels later described, cause the sheet of veneer to be discharged quickly and positively onto the tipple.

Referring now to FIG. 1B, the tipple 41 includes a frame 42 which is pivotally supported at its discharge end on a supporting structure 43 and is swingable up and down on a horizontal axis. The tipple frame 42 is also supported on a pair of hydraulic pistons and piston rods 44 (see also FIG. 8) which move up and down in hydraulic cylinders 44', the cylinders being pivotally mounted on suitable base supports.

The two pistons are operated in unison, the hydraulic fluid being delivered into and withdrawn from opposite ends of the cylinders 44' through conduits under the control of suitable solenoid-operated valves and the conduits are connected with a pump assembly operated by a motor M2 (FIG. 1B). The pump, valves, and controls for this hydraulic assembly are of well-known design and need not be described in detail since they do not constitute part of the present invention. The entire hydraulic assembly is so arranged and so controlled by automatic but adjustable switch means that the hydraulic pistons move the tipple from its lowermost position (in registration with the bottom deck 12 of the off-bearing section 11) to its highest position (registration with the top deck 17 of the off-bearing section 11) in a series of five moves occurring during equal periods of time, and then return the receiving end of the tipple from its highest position to its lowermost position quickly during a single equal period of time.

The delivery of the sheets of veneer from the respective decks of the off-bearing section 11 occurs during the upward travel of the receiving end of the tipple only. This feature of having the downward movement of one end of a tipple take place at a greater speed than the upward movement, with downward movement occurring entirely within the same amount of time required for the tipple to move upwardly from one deck or station to another, has been employed in other devices and consequently is not new in itself.

In order to maintain the up and down movement of the tipple exactly the same at both sides of the tipple, and thus to prevent the possibility of any slight tipping of the tipple towards one side or the other, which might be occasioned by a tendency for one hydraulic piston to move at slightly different speed from the other or over a slightly different distance, a pair of identical rack bars 45 (FIGS 1B and 8) have their upper ends pivotally attached to the tipple frame 42 at opposite sides. These rack bars move up and down in guideways in constant engagement respectively with a pair of identical pinions 46 (one of which is shown in FIG. 8) which pinions are secured on a common rotatably supported shaft 47.

The tipple is provided with a series of feed rolls 48 (FIG. 1B) which are joined at their ends by drive chains 49 and thus rotate in unison, and these are driven by chain or belt connection with the driving shaft of a motor M3. Pivotally supported press rolls 50 are arranged so as to rest on some of these feed rolls 48 and thus to bear on the veneer sheets which move along over the feed rolls 48 in order to keep the veneer sheets on the

tipple moving at the desired speed for which the motor M3 is set. The pivotally mounted or discharging end of the tipple, thus the right hand end as viewed in FIG. 1B), discharges onto an endless traveling conveyor C.

5 The conveyor C is driven by suitable means (not shown) and at suitable speed with respect to the operation of the tipple and its feed rolls, so that the veneer sheets delivered from the discharging end of the tipple will be deposited on the conveyor separated from such other and arranged in consecutive order.

10 The means by which the delivery of the sheets of veneer from the separate decks of the off-bearing section 11 onto the receiving end of the tipple 41 is automatically controlled will now be described with reference to FIGS. 2, 3, 4 and 5. As previously explained with reference to FIG. 1A, a pair of more rapidly driven delivery rolls are located consecutively along the discharging end of each of the decks of the off-bearing section 11. Thus the delivery rolls 33 and 33' are located consecutively at the discharging end of the lowest deck 12; the delivery rolls 34 and 34' are located at the discharging end of the deck 13; and so on. Pinch wheels are provided for the purpose of bearing down on the first delivery roll of each pair, and thus on the rolls 33, 34, 20 etc., so as to cause the veneer sheet, which has been moved into position between such delivery roll and its cooperating pinch wheels, to be thrust forwardly and discharged from the off-bearing section 11 onto the tipple at the proper time. Since similar pinch wheels are 25 provided for each of the delivery rolls 33, 34, etc., it will be sufficient to describe the mounting and manner of operation of the pinch wheels for the delivery roll 33 on the bottom deck of the off-bearing section.

30 A shaft 51 (FIGS. 3, 4 and 5) is rotatably mounted in the frame of the off-bearing section 11 parallel to and near to the roll 33 and above the path of the veneer sheets passing over the roll 33. Pairs of parallel brackets 52 (shown best in FIGS. 3 and 4) are carried by the shaft 51. A pinch wheel carriage 53 is pivotally mounted at 35 one end on a pin 54 carried by each pair of brackets 52. A lower pin 55 limits the downward swing of the wheel carriage 53. A pinch wheel 56 is supported in the opposite or free end of the carriage 53. A bar 57 (see FIG. 6) extends upwardly from the middle of the 40 pin 55 through an aperture in a cross web 53' of the carriage 53. The upper end of this bar 57 is threaded and carries an adjustable nut 58. A coil spring 59 is 45 carried on the bar 57 and is held under compression between the cross web 53' and the nut 58.

50 A pair of arms 60, secured to the end of the shaft 51, have a pivotal connection with a piston rod 61 which is operated by an air cylinder 62. Consequently, as apparent from FIGS. 2 and 4, movement of the piston rod 61 outwardly with respect to its cylinder 62 will cause the pinch wheels 56 to be moved downwardly against the delivery roll 33, while movement of the piston rod 61 in the opposite direction will lift the pinch wheels 56 above the delivery roll 33.

55 A fence shaft 63 is rotatably mounted in the frame of the off-bearing section 11 beyond the pinch wheel assembly and is connected by suitable link arms with the pinch assembly shaft 51 so as to be rotated with the pinch assembly shaft. An elongated narrow plate or stop fence 64 is secured to the shaft 63. As shown best in FIGS. 2 and 4, the arrangement is such that movement of a piston rod 61 to bring the pinch wheels 56 downwardly upon the delivery roll 33 will cause the stop fence 64 to be swung out into inoperative position; whereas movement of the piston rod 61 in the opposite direction will result in raising the pinch wheels from the delivery roll and in lowering the stop fence 64 into position for blocking the discharge of a veneer sheet from that particular deck to the off-bearing section 11.

60 Thus when the receiving end of the tipple 41 is moved down into proper position for receiving a veneer sheet

from the bottom deck of off-bearing section, for example, the delivery of compressed air into one end of cylinder 62, forcing the piston rod 61 outwardly, will cause the pinch wheels 56 to bear down on the veneer sheet as it rides on the roll 33 and result in the driving of the sheet rapidly forwardly, while the raising of the stop fence 64 at the same time allows the free passage of the veneer sheet from the deck of the off-bearing section onto the tipple. The delivery of compressed air to the opposite end of the cylinder causes the fence 64 to be lowered and the pinch wheels 56 to be raised. The stop fence 64 is in the lowered normal blocking position and the pinch wheels are in the raised inoperative position at all times except during the moment in which the sheet or sheets from that deck is to be discharged onto the tipple. Consequently a sheet of veneer or sheets of veneer which have reached the delivery roll 33 and its forward companion delivery roll 33' will temporarily be held in this location until the proper time for discharge onto the tipple. The adjustable coil spring 59 for each pinch wheel carriage enables the pinch wheels to press down with a desired amount of resilient force on the sheet of veneer which they engage when the sheet is to be discharged from the off-bearing section with the lifting of the stop fence.

The same combination of delivery rolls, pinch wheels, and stop fence is provided similarly for each deck of the off-bearing section 11. In order to enable these actuating mechanisms to be more compactly arranged at the side of the cooler the air cylinders and pinch wheel assemblies are somewhat differently positioned for alternate decks of the cooler, but their manner of operation is the same for each deck. Thus it will be observed from FIG. 2 that the cylinder 62' and the pinch wheel assembly shaft 51' for the next deck 13 are in relatively different locations from the locations of the cylinder 62 and pinch wheel assembly shaft 51 for the deck 12, but this is merely for convenience in arrangement. Due to the resulting spacing between the pinch wheel assembly shaft 51' and the fence shaft 63' for the deck 12, additional linkage is interposed between the two. For the deck 14 the arrangement is the same as for the first deck 12, and so on. While the air cylinders and the other operating mechanism for the pinch wheel assemblies and fence shafts are illustrated only on one side of the off-bearing section 11, preferably these are also provided at the opposite side of the off-bearing section as well, since the width of the dryer and the off-bearing section in most instances would make this desirable. Similarly, although the driving means for the feed rolls and delivery rolls are shown on only one side of the off-bearing section 11, for the sake of clarity, it is to be understood that such driving means are provided also at the opposite side.

The speed of operation of the entire device is automatically governed by the speed of the dryer and cooler, and the latter is regulated in the customary manner (not shown) with regard to the length and nature of the veneer sheets being handled, etc. An adjustable gear drive, located in a housing 65 mounted on one side of the off-bearing section 11 (FIGS. 1A and 7), is driven by belt connections 66 and 67 from one of the driven feed rolls 68 of the dryer and cooler 10. A shaft 69 (FIG. 7), rotated through the intermediary of the adjustable gear drive in the housing 65, carries a pair of cam discs 70 and 71 each of which has six equally spaced cam lobes (corresponding to the number of decks in the off-bearing section) which engage a contact element 72 or 73 upon the rotation of the cam disc. The discs are so arranged that their cam lobes are staggered with respect to each other. When the contact element 73 for the cam disc 71, for example, is connected through a suitable time delay relay to the circuits for the relays and solenoids controlling the actuation of the air cylinders which operate the stop fences and pinch wheels on the decks of the off-bearing section and for the relays and solenoids for the

hydraulic valves controlling the movements of the tipple, the successive engagement of the contact element 73 by the 6 cam lobes on the disc 71 during one revolution of the disc 71 will complete a cycle of operation of the device for the corresponding 6 decks of the off-bearing section with the proper timing for veneer sheets of a particular length, thus for sheets of the customary length of eight feet. However, if veneer sheets having a length of only four feet are to be handled in the device, then the contact element 72 for the other disc 70 is also connected into the same circuits, and, since the cam lobes on the two discs 71 and 70 are staggered with respect to each other, the connecting of the contact 72 as well as the contact 73 into the operating circuits and the adjustment of the time delay relay will double the speed of operation of the device by reducing the discharging period for the different decks by one-half, thus enabling the device to operate with full efficiency for four foot veneer sheets. Furthermore, by adjusting the hand wheel 74 (FIG. 7) of the ratio adjustment of the adjustable gear drive for the shaft 69, intermediate and further variations in the timing periods and thus in the speed of operation of the device are attainable to correspond to other lengths of veneer sheets, should the veneer sheets which are being put through the dryer be of some other length.

During any single period of operation of the veneer dryer and cooler, and thus of the off-bearing section, the veneer sheets will all be of the same length, the speed of operation of the dryer and cooler and the timing of the operation of the fences and pinch rolls in the off-bearing section and of the movements of the tipple being adjusted for the particular length of the sheets as previously indicated. However, while the sheets will all be the same length their widths may vary considerably. In order to prevent the possibility of any sheets deviating towards one side or the other from their course through the off-bearing section a plurality of small guide wheels 76 (FIG. 1A) are provided on each deck of the off-bearing section. These wheels are mounted on pivoted arms 75 and ride on the feed rolls except when engaged by the veneer sheets. The guide wheels are spaced a short distance apart transversely with respect to the forward direction of travel of the sheets and thus a guide wheel would engage the side edge of any sheet which attempted to turn towards one side.

A bar 84 (FIG. 1B), attached to the frame 42 of the tipple 41, supports a carriage 83 which slides up and down in a guideway 85 with the up and down movement of the tipple. The carriage 83 has a member 83' which engages actuating elements for switch assemblies arranged in a succession of six switch boxes 77", 78", 79", 80", 81" and 82" so positioned that the travel of the moving or receiving end of the tipple intermittently from the lowest deck 12 to the top deck 17 (FIG. 1A) of the off-bearing section 11 will cause the switch assemblies to be engaged respectively. The controlled movement of the tipple 41 is such that when the tipple is in its lowest position, thus receiving the veneer sheet or sheets from the bottom deck 12 of the off-bearing section 11, the member 83' will be in engagement with the actuating element in the lowest switch box 77". The tipple remains in this position for a predetermined period of time during which the stop fence for the discharging end of the lowest deck 12 of the off-bearing section is raised and the pinch wheels for that deck are lowered, such period of time being sufficient to allow the sheet or sheets of veneer from the end of the deck 12 to be discharged onto the tipple. Then the tipple moves quickly up to the next deck of the off-bearing section and remains at the next deck for the same predetermined period, the member 83' then engaging the actuating element in the next switch box 78", and so on. When the tipple arrives at the top deck it remains there for the same predetermined period, with the member 83' engaging the actuating element in the switch box 82". The tipple next moves rapidly all the way down to its

lowest position, moving five times as fast as during each of its upward movements.

The actuation of the solenoids for the hydraulic valves governing the movement of the tipple, the actuation of the solenoids for the air valves controlling the air cylinders and pistons which operate the stop fences and pinch wheels on the corresponding decks of the off-bearing section, and the connected time delay elements all function automatically in accordance with the speed at which the entire device is set to operate, and the speed in turn is governed by such conditions as the speed of the dryer and cooler and the length of the veneer sheets being handled, as previously mentioned.

The manner in which the operations are coordinated and automatically controlled can be explained briefly and more clearly with reference to the special schematic diagram of FIG. 10. In this schematic diagram all unimportant wiring details have been omitted for the sake of simplicity and clarity.

In FIG. 10, in which L1 and L2 are the two power line conductors, the solenoids for the air valves for the air cylinders operating the stop fences and pinch wheels on the six decks of the off-bearing section are indicated at 12', 13', 14', 15', 16' and 17' respectively. In describing the operation it is assumed first that the device is being used for veneer sheets of the standard length of eight feet. It is assumed also at the start that the tipple is in registration with the bottom deck 12, as indicated in FIG. 1A and FIG. 2. In this position of the tipple the engagement of the member 83' (FIG. 1B) with the element in the switch box 77" causes the switch 77 (FIG. 10) to be opened and its companion related switch 77' to be closed. The time switch contacts 112 and 113 for the cam disc 71 (FIG. 7) are manually set and closed. With the rotation of cam disc 71 the engagement of any one of its six cam lobes with the contact element closes the contact (indicated by the switch 73 in FIG. 10) momentarily. This activates the time delay relay 86 which operates to close the time switch 87. The activation of 86 momentarily also closes switch 88, activating time delay switch 89 through the normally closed switch 98 and the previously manually closed time switch 113. Activation of 89 closes the holding circuit switch 90 and in addition closes switch 91. The closing of switch 91 momentarily causes current to pass through the by-pass line to the control relay 93 through the normally closed switch 92. The control relay 93 operates to close holding switch 94 and switch 95. Switch 95 causes activation of solenoid 96 through the normally closed switch 107. Solenoid 96 operates a valve in the hydraulic system for the tipple which starts the tipple moving upwardly. Switch 95 is connected with by-pass switch 92 so that the closing of switch 95 opens by-pass switch 92. Since the switch 77 returns to its normal closed position immediately the tipple starts moving upwardly, the circuit to control relay 93 momentarily remains closed and thus holds switch 95 closed and solenoid 96 remains activated with the tipple moving upwardly. The closing of switch 95 activates the time delay element 97 to hold switch 92 open. The activation of relay 93 also opens switch 98 thereupon rendering switch 89 inactive which opens switches 90 and 91 and causes switch 89 to be reset for the next cycle. When the tipple reaches the second deck 13 the switch 78 is opened and the related switch 78' is closed. The opening of switch 78 interrupts the circuit to control relay 93 which opens switches 94 and 95, allows switches 92 and 98 to close, and deactivates solenoid 96, causing the tipple to stop its upward movement. The opening of switch 78 causes the closing of the related switch element 78' and the activation of solenoid 13' which opens the stop gate and lowers the pinch wheels on the second deck 13 of the off-bearing section.

This cycle of switch operations is repeated five times as the tipple moves upward in intermittent periods, each cycle being caused by the closing of the contact 73 by the en-

agement of the cam lobe on the disc 71 with its contact.

When the tipple reaches the top deck and opens switch 82 and closes the companion switch 82', activating solenoid 17' and causing the veneer sheet from the top deck 5 17 to be delivered onto the tipple, the opening of switch 82 closes a connected switch 82A which activates control relay 99. This relay 99 closes switch 101. The activation of current relay 93 through by-pass switch 92 closes switch 102, and, since switch 101 is closed the relay 103 10 is now activated. This relay opens switch 107 and closes switch 105. Switch 105 activates solenoid 106 which produces the downward movement of the tipple. The relay 103 also closes the holding circuit switch 104. When the tipple reaches the lower deck 12 the switch 77 15 is opened and the next cycle starts. Manual control switches are indicated at 129 and 108.

If four foot sheets are now to be handled in place of eight foot sheets the circuit will be closed through the switch 72 as well as through the switch 73. In other 20 words both discs 70 and 71 (FIG. 7) will govern the time period cycle. Manual switch 72' is closed to enable the closing of switch 72 by its disc to become effective. The time delay relay switches 114 and 116 are also manually closed at the same time thus enabling time delay relays 25 115 and 117 to function in the same manner as the time delay relays 112 and 113 previously mentioned. Now time delay relay 115 operates to close switch 87' and switch 115, and time delay relay 117 operates the holding switch 109 and switch 111. The operation throughout the cycle is as previously described but since each 30 cycle occurs alternately by the closing of the contacts for both cam discs with their cam lobes staggered, and thus by the alternate closing of switches 73 and 72 as illustrated in FIG. 10, the cycles take place twice as rapidly, 35 and consequently the entire device is speeded up so as to handle veneer sheets of four feet in length instead of eight feet in length with similar efficiency.

As previously indicated, the cycles of operation can be varied further by adjusting the adjustable gear drive connection 40 by which the disc shaft 69 is driven from the driving rolls of the dryer and cooler. Thus the entire off-bearing assembly including the off-bearing section 11 and the moving tipple can be adjustably set to operate automatically at the speed desired with respect to the 45 speed of the dryer and cooler and the length of the veneer sheets being handled, and the sheets will be delivered at the desired rate, separately and consecutively, onto the continuous moving conveyor C.

While the device has been illustrated and described for 50 use with a six deck dryer and cooler, and thus with the off-bearing section of the device providing the corresponding six decks, it is of course to be understood that the actual number of decks may be varied.

I claim:

55. In equipment for unloading sheets of material from a multiple deck conveyor assembly of the character described, control elements on the discharge end of each deck of the conveyor assembly for controlling the discharge of material from such assembly deck, said discharge control elements for each deck including a rotating delivery roll, pinch wheels positioned above said delivery roll, a stop fence located beyond said pinch wheels and delivery roll in the direction of travel of material on the deck, and means for moving said pinch wheels downwardly towards and upwardly from said delivery roll and for raising and lowering said stop fence, a switch assembly 60 for each deck controlling the operation of said means, a tipple pivotally mounted at its discharging end on a fixed support and having a receiving end movable up and down into registration successively with the discharge ends of the conveyor decks, switch actuating means carried by said tipple, cooperating switches connected respectively with said switch assemblies on the decks of the multiple deck conveyor, said cooperating switches positioned 65 for engagement separately by said switch actuating means
- 70
- 75

as said receiving end of said tipple moves into registration with each corresponding deck, whereby said switch assembly for each deck will be operated to move the control elements for that deck into discharging position when said receiving end of said tipple is in registration with that deck, means for automatically moving said receiving end of said tipple up and down, and means controlling the speed of operation of said tipple moving means.

2. In equipment for unloading sheets of material from a multiple deck conveyor assembly, control elements on the discharge end of each deck of the conveyor assembly for controlling the discharge of material from the deck, means on each deck for operating said discharge control elements for that deck, a switch assembly for each deck controlling the operation of said means, a tipple pivotally mounted at its discharging end on a fixed support and having a receiving end movable up and down into registration successively with the discharge ends of the decks, switch actuating means carried by said tipple, cooperating switches connected respectively with said switch assemblies on the decks of the multiple deck conveyor, said cooperating switches positioned for engagement separately

5 by said switch actuating means as said receiving end of said tipple moves into registration with each corresponding deck, whereby said switch assembly for each deck will be operated to move the control elements for that deck into discharging position when said receiving end of said tipple is in registration with the deck, means for automatically moving said receiving end of said tipple up and down, and adjustable means controlling the speed of operation of said tipple moving means.
